UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

UNCOUPLING MECHANISM FOR CARS.

1,123,165.

Specification of Letters Patent. Patented Dec. 29, 1914.

Application filed April 5, 1912. Serial No. 688,792.

To all whom it may concern:

Be it known that I, PAUL M. BEARD, a citizen of the United States, residing at St. Louis, Missouri, have invented a certain new and useful Improvement in Uncoupling Mechanism for Cars, of which the following is a full, clear, and exact description, such as will enable others skilled in the art to which it appertains to make and use the same, reference being had to the accompanying drawings, forming part of this specification, in which—

Figure 1 is an end elevation of a car end sill and coupler, and showing my improved uncoupling mechanism applied thereto. Fig. 2 is a plan view of the parts seen in Fig. 1. Fig. 3 is a cross section taken approximately on the line 3—3 of Fig. 1.

This invention relates to new and useful improvements in uncoupling mechanisms for cars, my object being to provide simple means for elevating the coupling pin to release the knuckle of the coupler, and which uncoupling means includes a pin elevating arm or lever, and an actuating lever, which parts are fulcrumed and connected so that when the free end of the actuating lever is moved vertically in either direction, the end of the pin elevating arm or lever is elevated, thereby carrying the coupler pin upward to permit the knuckle to swing outward as the cars are drawn apart.

By my improved construction, it is possible for an operator to engage and move the actuating lever from a position on the car above the end sill, as well as from a position on the ground.

Further objects of my invention are to provide an uncoupling mechanism having a minimum number of parts in order to reduce the liability of said parts getting out of order and becoming inoperative, and further to arrange the fulcrums and pivot points of the two members of the mechanism so that the power applied to the actuating lever is utilized to the greatest advantage in moving the pin elevating arm, and for this reason, the mechanism can be actuated with comparatively little effort on the part of the operator.

To the above purposes, my invention consists in certain novel features of construction and arrangement of parts hereinafter more fully described and claimed.

In the drawings, 1 designates the end sill,

2 the coupler head, and 3 the locking pin of said coupler, which pin is usually provided in its upper end with a transverse aperture.

Fixed in any suitable manner to the end sill 1, a short distance outward to the side of the center thereof, is an outwardly projecting pivot lug 4 that forms one of the fulcrums for the pin elevating arm. A second pivot lug 5 extends forwardly from the end sill 1 a short distance from the first lug 4, which second lug forms one of the fulcrums for the pin elevating arm and both of said lugs preferably occupy the same plane with the top of the end sill 1.

The pin elevating arm or lever 6, has one end formed into a short horizontally disposed rod 7 that passes through the aperture in the upper end of the coupler pin 3, and the end of said rod is formed into a transverse hook 8 that prevents the elevating arm from becoming disengaged from the coupler pin when these parts are elevated. The opposite end portion of the arm or lever 6 is bent so that it normally bears on top of the pivot lug 4 and beneath the pivot lug 5. The actuating lever 9 is in the form of a straight bar having its one end bent upwardly and formed into a hook 10 that embraces the arm or lever 6 at a point between the pivot lugs 4 and 5.

The lever 9 is fulcrumed near its inner end upon a pivot pin 11 projecting outwardly from the end sill and the outer end of said lever is formed into a handle 12 that normally occupies a position immediately adjacent to and slightly below the corresponding end of the end sill 1.

When it is desired to actuate the uncoupling mechanism and the operator is on the ground, the handle 12 is manually engaged and moved upward, thereby swinging said lever upon its fulcrum, which is the pivot pin 11, and the hook 10 on the inner end of said lever bears downwardly on top of the arm 6 at a point midway between the pivot lugs 4 and 5, thereby swinging said arm upon its fulcrum, which is the pivot lug 4, and elevating the free end of said arm and the coupler pin carried thereby.

When the operator is on the car and it is desired to operate the uncoupling mechanism, the operator places his foot upon the handle 12 and bears downwardly thereupon, which movement elevates the inner end of the actuating lever 9, and the hook 10 car-

ried by said inner end will bear upwardly against that portion of the arm 6 between the pivot lugs 4 and 5, and thus the pin carrying arm swings upwardly from the pivot lug 5, which now performs the function of a fulcrum and thus the coupler pin is elevated to free the knuckle.

It will be noted that in my improved uncoupling mechanism, but two operating parts are utilized and therefore the liability of the mechanism getting out of order and becoming inoperative is reduced to a minimum.

The actuating lever is operatively connected to the pin elevating arm at a point preferably midway between the pivot lugs which form fulcrums for said elevating lever, and the pivot point of said actuating arm is located immediately adjacent to the pivot lugs. By such arrangement the pin elevating arm can be elevated with the application of comparatively little power to the outer end of the actuating lever.

It will be readily understood that minor changes in the size, form and construction of the various parts of my improved uncoupling mechanism can be made and substituted for those herein described without departing from the spirit of my invention, 30 the scope of which is set forth in the appended claims.

I claim:

1. In an uncoupling mechanism, a pin engaging arm, two fixed fulcrums therefor, 35 an actuating lever coöperating with said arm, which lever has a fixed fulcrum.
2. In a car uncoupling mechanism, a pin engaging lever having a pair of fulcrums, and a fulcrumed actuating lever operatively 40 connected to the pin engaging lever between the fulcrums thereof.

3. In a car uncoupling mechanism, a pin engaging lever, a pivot lug against which the under side of the arm engages, a second pivot lug against which the upper side 45 of the arm engages, and an actuating lever operatively connected to said arm between the pivot lugs.

4. The combination with a railway car body, and coupler, having a locking pin, of 50 an arm connected to said locking pin, a pair of pivot lugs for said arm, and an actuating lever operatively connected with said arm between said pivot lugs, which lever has a fixed fulcrum.

5. The combination with a car body, and a coupler having a locking pin, of a pin engaging arm having two fixed fulcrums, and a fulcrumed actuating lever coöperating with said pin engaging arm.

6. The combination with a car body, and a coupler having a locking pin, of a pin engaging arm having two fulcrums, one above and one below said arm, and a fulcrumed actuating lever coöperating with 65 said pin engaging arm.

7. An uncoupling mechanism comprising an arm, fixed pivot lugs engaging said arm on opposite sides to form a pair of fulcrums for said arm, and means having a fixed fulcrum engaging said arm for swinging the same upon either one of the pivot lugs.

8. A two-part uncoupling lever, one of which parts has two fixed fulcrums and the other part having a single fixed fulcrum.

In testimony whereof I hereunto affix my signature in the presence of two witnesses, this third day of April, 1912.

PAUL M. BEARD.
